UNITED STATES PATENT OFFICE.

WILLIAM A. READY, OF BROOKLINE, MASSACHUSETTS.

DIAL MECHANISM FOR RADIO APPARATUS.

Application filed March 16, 1926. Serial No. 95,154.

My invention aims to provide improvements in dial mechanisms particularly adapted for use in connection with securing the fine adjustment of rotary parts of instruments of radio apparatus.

The invention consists in the combination and arrangement of parts set forth in the following specification and particularly as pointed out in the claims thereof. The construction herein disclosed is in some respects similar to constructions disclosed in one or more of my co-pending applications which contain claims generic to certain features embodied in the structure shown in the present application and also to specific features which I have elected to prosecute in such other co-pending applications.

Referring to the drawings:

Figure 1 represents a side elevation of a variable condenser for a radio apparatus, the variable vernier mechanism embodying my invention being operatively connected thereto and illustrated partly in section and partly in elevation.

Fig. 2 is a front elevation of the mechanism as viewed from the right of Figure 1, the operating knob being removed from the driving member.

Fig. 3 is an enlarged central vertical section through the driving member, the latter engaging the driven member to drive the same at its maximum ratio of angular displacement.

Fig. 4 is a detail sectional elevation as taken on the line 4—4, Fig. 3.

Fig. 5 is a detail elevation illustrating the relative positions of the driving and driven members when the former is positioned to drive the latter at its minimum ratio of angular displacement.

Like numerals refer to like parts throughout the several views of the drawings.

In the drawings, 5 represents a variable condenser of well-known form, the same being mounted in any suitable manner upon a panel 6. The condenser 5 embodies therein a frame 7, upon which a plurality of rotor plates 8 are mounted in any suitable manner upon a rotor or dial shaft 9, the latter being journaled in said frame 7. Also mounted upon the frame 7 are a plurality of stator plates 10, the latter being mounted in any suitable manner upon posts 11 and 12, which,

in turn, are mounted in insulating blocks 13 and 14 respectively, fastened to said frame.

In order that a very delicate adjustment may be obtained between the rotor and stator plates, a variable vernier mechanism is provided for the condenser 5 with cooperating indicating means and dial cover means hereinafter described. Mounted upon the outer extremity of the rotor shaft 9, upon the opposite side of the panel 6 from that upon which the condenser 5 is mounted is an auxiliary panel or face plate 15, and all of the parts of the vernier mechanism are mounted upon said auxiliary panel and so assembled as to constitute a self-contained unit which may be attached to or removed from said rotor shaft in its entirety at any time without disturbing any of the various parts thereof. The panel or face plate 15 has a rim at its periphery to provide a shallow compartment at the rear of the panel for housing the vernier driving means hereinafter more fully described.

Mounted upon the exterior of the auxiliary panel 15 is a socket or bushing 16 having a shouldered portion 17 formed thereon which projects through said auxiliary panel, and located within a recess 18 provided at the rear of said panel is a disc 19 constituting a driven member, the opposite faces of which are beveled slightly at 20 and 21 adjacent to the periphery thereof. The beveled surfaces 20 and 21 are so related to each other that if extended outwardly so that they would intersect, they would form an acute angle of approximately 10°. The bushing 16 in effect forms a hub for the disc 19 and is rigidly secured to the rotor shaft 9 by a screw 22.

The front face of the disc 19 is provided with a shallow recess 23 in which an indicator 24 of sheet material is rigidly secured in any suitable manner, the front face of said indicator being flush with the front surface of said disc. The indicator 24 is provided with a plurality of graduations 25 and reference characters 26 which are visible through an opening 27 provided in the auxiliary panel 15. A thin transparent member 28 is secured to the rear of the auxiliary panel 15 and extends across the opening 27 and said transparent member has an opening 29 formed therein, thereby enabling the operator of the radio apparatus to mark the designations of

the different radio stations upon the surface of the indicator 24 at points opposite the graduations 25.

Also mounted upon the auxiliary panel 15, 5 parallel with the rotor shaft 9, is a driving member 30 also constituting a vernier shaft, the latter being rotatable within a bearing member 31 which, in turn, is rotatable within the auxiliary panel 15. The bearing member 10 31 has a resilient operating arm 32 rigidly fastened thereto, at the outer extremity of which is a pin 33 which is adapted to spring into any one of a plurality of recesses 34 provided in the auxiliary panel 15 and arranged 15 concentric with the axis of the bearing member 31. The spring tension upon the resilient arm 32 furthermore acts to hold a shouldered portion 35 of the bearing member 31 against a correspondingly shouldered portion provided upon the auxiliary panel 15. Stop pins 20 36 are provided adjacent to the opposite extremities of the row of recesses 34 for the purpose of limiting the extent to which the bearing member 31 may be moved by the 25 operating arm 32, the pin 33 of which engages each of said stop pins.

The driving member, or vernier shaft 30, embodies therein a friction member 37, the axis of which is eccentrically disposed to the 30 axis of the bearing member 31 in which said friction member is mounted to rotate. The friction member 37 has a bevelled face 38 formed thereon which is opposite to and engages with the bevelled face 21 of the disc 19.

35 Another friction member 39 is slidably mounted within the friction member 37, the axis of said friction member 39 being coincident with the axis of the friction member 37. The friction member 39 has a bevelled face 40 which is oppositely disposed to and engages with the bevelled face 20 of the disc 19. The friction member 39 has a shouldered stem portion 41 formed integral therewith which extends through the friction 40 member 37 and the latter has a recess 42 provided therein in which a spiral spring 43 is located, said spring encircling said stem 41, and one end of said spring engages the friction member 37 at the bottom of the recess 45 42, while the opposite end of said spring engages a collar 44 mounted upon the stem 41 and held thereon by a pin 45. The action of the spring 43 is such that the friction members 37 and 39 are held in yielding engagement with the bevelled faces 21 and 20 respectively of the disc 19. The pin 45 at its opposite ends extends into a groove 46 provided in the adjacent extremity of the friction member 37 and said members will, therefore, 55 rotate in unison.

An operating knob 47 is rigidly secured to the friction member 37 by a set screw 48, and a spring washer 49 is mounted upon the friction member 37 and is interposed between 60 said operating knob and the rocker member

31 and acts to hold a tapered shouldered portion 50 of said friction member 37 within a correspondingly tapered recess provided in the rocker member 31.

It is desirable in transmitting the rotary motion from the driving member 30 to the driven member 19 that the speed of the rotor shaft shall be considerably reduced, and to effect this result the diameter of the friction members 37 and 39 is considerably less than 75 that of the disc 19 and the speed of the driven member 19 may be still further reduced as compared to that of the driving member 30 by moving the bearing member 31 within the panel 15 and moving the median 80 line of said driving member nearer to that of said driven member, at which time the friction members 37 and 39 will engage the disc 19 approximately as illustrated in Fig. 5, thereby changing the effective ratio between the driving and driven members.

In tuning the radio apparatus, the rotor plates 8 of the condenser 5 are adjusted relatively to the stator plates 10 by rotating the operating knob 47 and the rotary motion from said knob is transmitted through the driving member or vernier shaft 30 to the driven member 19, the latter travelling at a greatly reduced speed from the speed of the operating knob 47.

If the operating arm 32 of the bearing member 31 is positioned with the pin 33 thereof located within the extreme left-hand recess 34 of the auxiliary panel 15, the relative positions of the friction members 37 and 39, with relation to the disc 19, will be as illustrated in Fig. 3, at which time the effective ratio of the driving member to the driven member is approximately seven to one.

If, however, the operating arm 32 is moved to locate the pin 33 within the extreme right-hand recess 34, the relative positions of the friction members 37 and 39, with relation to the disc 19, will be as illustrated in Fig. 5, at which time the effective ratio between the driving and driven members will be approximately eighteen to one.

It will be observed that in transmitting the rotary motion from the operating knob 47 to the rotor shaft 9, through the friction members 37 and 39 and disc 19 that there will be absolutely no backlash or lost motion and the members 37 and 39 will always tightly grip the opposite faces of the disc 19. In mounting the auxiliary panel 15 to the panel 6 of the radio receiver, I have provided means in the form of a pin 60 Fig. 1 which engages both panels and prevents turning of the auxiliary panel 15 relative to the panel 6. As the bushing 16 holds the auxiliary panel against the panel 6, I have provided means which cooperate to hold the auxiliary panel in given relation with the panel 6 of a radio receiver or like device.

While I have illustrated and described my invention somewhat specifically, I do not wish to be limited thereby and, therefore, reference is made to the following claims to indicate the scope of my invention.

I claim:

1. A radio apparatus having, in combination, a rotary driven member, an indicator fast thereto, a driving member comprising 10 a pair of friction members, means to hold said members in frictional engagement with the opposite faces of said driven member, whereby a rotary motion may be imparted to said indicator by the rotation of said driving member, and said driven member held in adjusted position, eccentric means to move said driving member relatively to said driven member to change the position of the point of contact therebetween, whereby the effective 20 ratio between said members is varied, and means to lock said last-named means in its various positions.

2. A vernier mechanism for a radio apparatus having, in combination, a panel, 25 a driven member comprising a disc rotatably mounted with relation to said panel, an indicator fast to said disc, a rotatable bearing mounted in said panel, a driving member comprising a pair of friction members 30 mounted in said bearing, and means to hold said friction members in engagement with the opposite faces of said disc, whereby a rotary motion may be imparted to said indicator by the rotation of said friction members, said bearing being adapted to move 35 said friction members to change the position of their point of contact with said disc, whereby the effective ratio between said driving member and driven member is 40 varied.

3. A dial mechanism for a radio condenser comprising, in combination, a dial, a shaft therefor adapted for connection with the rotor shaft of the condenser, and carrying a 45 single large disc, a vernier shaft having a pair of smaller discs mounted thereon and arranged to receive the edge of said single disc therebetween, spring means pressing said pair of discs against said single disc to 50 form a frictional driving contact therebetween, a bearing for said vernier shaft having its axis eccentric to the axis of said vernier shaft, and means for rotating said bearing to move said vernier shaft toward or 55 away from said dial shaft whereby the contact relation between said pair of discs and said single disc is varied to effect different driving ratios between the shafts.

4. A vernier mechanism for a radio apparatus having, in combination, a panel, a driven member comprising a disc rotatably mounted upon said panel, said disc being 60 beveled upon its opposite faces adjacent to the periphery thereof, a dial fast to said disc, 65 a rotatable bearing member mounted on said

panel, a friction member mounted in said bearing eccentric to the axis thereof and provided with a beveled surface engaging a beveled surface of said disc, a second friction member slidably mounted in said first-named, 70 friction member and provided with a beveled surface engaging the other beveled surface of said disc, means to hold said friction members in yielding engagement with said disc, whereby a rotary motion may be imparted to said dial by the rotation of said friction members, said bearing member being adapted to move said friction members to change the position of their point of contact with said disc, whereby the effective 75 ratio between said disc and friction members is varied, and means to lock said bearing member in different positions upon said panel.

5. A vernier mechanism for a radio apparatus having, in combination, a panel, a driven member comprising a disc rotatably mounted upon said panel, said disc being beveled upon its opposite faces adjacent to the periphery thereof, a dial fast to said disc, 90 a bearing member mounted on said panel, a friction member mounted in said bearing member eccentric to the axis thereof and provided with a beveled surface engaging a beveled surface of said disc, a second friction member 95 slidably mounted in said first-named friction member and provided with a beveled surface engaging the other beveled surface of said disc, a spring interposed between said friction members and forcing 100 said members into yielding engagement with said disc, whereby a rotary motion may be imparted to said dial by the rotation of said friction members, said bearing member being adapted to move said friction members 105 to change the position of their point of contact with said disc, whereby the effective ratio between said disc and friction members is varied, and a resilient arm fast to said bearing member adapted to yieldingly engage 110 said panel and lock said rocker member in different positions relatively thereto.

6. An attachment for effecting fine adjustments of a condenser or the like comprising a hub member having a socket to receive the end of the shaft of the instrument to be adjusted and provided with a set screw entered through the side of said socket by which said hub member may be adjustably secured on said shaft, said set screw being exposed at 115 the front of the attachment and thereby enabling connection of the hub to the device to be adjusted, a thin disc attached to the rear portion of said hub and by which said hub may be rotated, a thin flat case covering 120 said disc, said case having a bearing for the hub holding the hub and case assembled in definite relation with the hub exposed at the back of the case and where- 125 by the device may be applied as a unit 130

over the face of an instrument panel with the thin flat case close against the face of the panel and the hub attachable to the end of an instrument shaft projecting through the 5 panel, a pair of smaller opposed driving discs journaled in the case with their edges in gripping engagement over the edge portion of the larger first mentioned disc and a handle member exposed at the front of the case for operating said opposed driving discs.

7. An attachment for effecting fine adjustments of condensers or other instruments, comprising a face plate with a narrow flange about the edge portion of the same providing 15 a shallow chamber at the back of said face plate, a hub member journaled in said face plate, said member being exposed at the rear for engagement with the projecting end of an instrument shaft and provided with means 20 by which the same may be secured to said instrument shaft, a disc member secured to said hub member and operating in the shallow chamber at the back of the face plate, an operating knob member at the front of the 25 face plate, co-operating opposed spring tensioned driving discs actuated from said knob member and journaled in the face plate with their opposing edges in gripping engagement over an edge portion of the hub disc and co- 30 operating indicating means on the face plate and actuated from the hub respectively for visualizing the rotative adjustments of the hub effected by the knob member.

8. An attachment for effecting fine adjustments of a condenser or like instrument comprising a face plate having a rearwardly flanged rim providing a shallow compartment at the back of the face plate, a hub journaled in said face plate, said hub being exposed at the back of the face plate to engage 40 the projecting end of an instrument shaft and provided with means exposed at all times and accessible at the front of the face plate for securing said hub in adjusted relation to the shaft, an adjusting member journaled in the face plate and accessible for operation at the front of the face plate and driving connections at the back of the face plate and housed in the shallow compartment aforesaid, 45 said driving connections extending from said adjusting member to the hub and proportioned to effect a reduced motion of the hub by rotary movement of the adjusting member.

55 9. An attachment for effecting fine adjustments of a condenser or like instrument comprising a face plate having a rearwardly flanged rim providing a shallow compartment at the back of the face plate, a hub journaled in said face plate, said hub being exposed at the back of the face plate to engage 60 the projecting end of an instrument shaft and provided with means accessible at the front of the face plate for securing said hub in adjusted relation to the shaft, an adjusting 65

member journaled in the face plate and accessible for operation at the front of the face plate, driving connections at the back of the face plate and housed in the shallow compartment aforesaid, said driving connections 70 extending from said adjusting member to the hub and proportioned to effect a reduced motion of the hub by rotary movement of the adjusting member, co-operating indicating means carried by the hub and face 75 plate respectively and means for securing said face plate with respect to a panel or the like to render the face plate a fixed support for the adjusting member and the indicating means of the face plate fixed with respect to 80 the co-operating relatively movable indicating means of the hub.

10. In a radio dial installation in combination with a panel having a revolvably adjustable shaft projecting therethrough, an 85 inscribable dial on the shaft having a scale thereon, a cover for the dial, said cover being apertured to expose a portion of the scale and to provide for access of a writing instrument through the cover to provide for inscription 90 of a designation of adjustment on said dial in addition to said scale.

11. In a radio dial installation in combination with a panel having a revolvably adjustable shaft projecting therethrough, an 95 inscribable dial on the shaft having a scale thereon, a cover for the dial, said cover being apertured to expose the graduations of the scale and independently to expose a portion 100 of the dial face apart from the graduations to permit access thereto of a marking instrument.

12. In a radio dial installation in combination with a panel having a revolvably adjustable shaft projecting therethrough, a disc or 105 dial adapted to be secured to said shaft, a cover plate mounted in front of the panel and having an aperture therethrough to expose tuning indicia presented by the disc or dial means securing the cover plate against the 110 panel and a knob or handle exposed at the front of the cover plate and connected for turning the disc or dial.

13. In a radio dial installation in combination with a panel having a revolvably adjustable shaft projecting therethrough, a disc or dial adapted to be secured to said shaft, a cover plate mounted in front of the panel and having an aperture through which the end of the shaft passes, a knob attached to the shaft 115 and provided with a bearing designed for holding the cover plate against the panel and means for interlocking engagement between the panel and the cover plate to prevent rotation of the cover plate relative to the panel. 120

14. In a radio dial installation in combination with a panel having a revolvably adjustable shaft projecting therethrough, a disc or dial adapted to be secured to said shaft, a cover plate mounted in front of the panel and 125

- having an aperture through which the end of the shaft passes, a knob attached to the shaft and provided with a bearing designed for holding the cover plate against the panel, 5 means for interlocking engagement between the panel and the cover plate to prevent rotation of the cover plate relative to the panel, an aperture through the panel to expose tuning indicia carried by the disc or dial and 10 vernier means for rotating said disc or dial at a reduced ratio.
15. An attachment for effecting fine adjustment of a condenser or like instrument comprising a face plate adapted to be secured in fixed relation to the panel of a radio set or like instrument and having a rearwardly flanged rim providing a shallow compartment at the back of the face plate, means exposed at the back of said face plate to engage 20 the projecting end of an instrument shaft, fastening means for securing said means to the instrument shaft, hand operated means exposed at the front of said face plate for manual rotation, driving connections housed in said compartment and connecting the hand operated means and the means for engagement with the instrument shaft whereby rotation of the hand operated means produces reduced motion of the instrument shaft and 25 cooperating indicating means for showing the degree of rotation of the shaft.
30. 16. An attachment for effecting fine adjustment of a condenser or like instrument comprising a face plate adapted to be secured in fixed relation to the panel of a radio set or like instrument and having a rearwardly flanged rim providing a shallow compartment at the back of the face plate, means exposed at the back of said face plate to engage the projecting end of an instrument shaft, fastening 35 means for securing said means to the instrument shaft, hand operated means exposed at the front of said face plate for manual rotation, driving connections housed in said compartment and connecting the hand operated means and the means for engagement with the instrument shaft whereby rotation of the hand operated means produces reduced motion of the instrument shaft and 40 cooperating indicating means including an inscribed disc carried by said larger disc and rotatable therewith, an opening in said face plate for exposing said dial and a fixed indicator point located adjacent to the opening in the face plate whereby the degree of rotation of the shaft may be observed.
45. 17. An attachment for effecting fine adjustment of a condenser or like instrument comprising a face plate adapted to be secured in fixed relation to the panel of a radio set or like instrument and having a rearwardly flanged rim providing a shallow compartment at the back of the face plate, means exposed at the back of said face plate to engage the projecting end of an instrument shaft, fastening 50 means for securing said means to the instrument shaft, hand operated means exposed at the front of said face plate for manual rotation, driving connections housed in said compartment and connecting the hand operated means and the means for engagement with the instrument shaft whereby rotation of the hand operated means produces reduced motion of the instrument shaft, cooperating indicating means for showing the degree of rotation of the shaft and means for moving said discs laterally relative to each other for changing the ratio of rotation of one disc relative to the other.
55. 18. An attachment for effecting fine adjustment of a condenser or like instrument comprising a face plate adapted to be secured in fixed relation to the panel of a radio set or like instrument and having a rearwardly flanged rim providing a shallow compartment at the back of the face plate, means exposed at the back of said face plate to engage the projecting end of an instrument shaft, fastening 60 means for securing said means to the instrument shaft, hand operated means exposed at the front of said face plate for manual rotation, friction driving connections including a relatively large disc and a small disc housed in said compartment and connecting the hand operated means and the means for engagement with the instrument shaft whereby rotation of the hand operated means produces reduced motion of the instrument shaft and cooperating indicating means for showing the degree of rotation of the shaft.
65. 19. An attachment for effecting fine adjustment of a condenser or like instrument comprising a face plate adapted to be secured in fixed relation to the panel of a radio set or like instrument and having a rearwardly flanged rim providing a shallow compartment at the back of the face plate, means exposed at the back of said face plate to engage the projecting end of an instrument shaft, fastening 70 means for securing said means to the instrument shaft, hand operated means exposed at the front of said face plate for manual rotation, friction driving connections including a relatively large disc and a small disc housed in said compartment and connecting the hand operated means and the means for engagement with the instrument shaft whereby rotation of the hand operated means produces reduced motion of the instrument shaft and 75 cooperating indicating means for showing the degree of rotation of the shaft.
80. 20. A dial mechanism for a radio appa- 85

tus, comprising in combination, a manually operable vernier shaft, a dial shaft parallel to said vernier shaft, friction driving means operatively connecting said shafts whereby 5 rotation of the vernier shaft produces reduced rotation of the dial shaft, a bearing for one of said shafts in which the shaft is eccentrically mounted, adjusting means operative to turn said bearing, thereby to move

one shaft laterally relative to the other shaft 10 for changing the ratio of rotation of one shaft relative to the other and cooperating indicating means for showing the degree of rotation of the dial shaft.

In testimony whereof I have hereunto set 15 my hand.

WILLIAM A. READY
